UNITED STATES PATENT OFFICE.

MITCHEL E. DEVARNEY, OF ST. ALBANS, VERMONT.

BOTTLE.

1,106,030.

Specification of Letters Patent.

Patented Aug. 4, 1914.

Application filed February 9, 1914. Serial No. 817,528.

To all whom it may concern:

Be it known that I, MITCHEL E. DEVARNEY, a citizen of the United States, residing at St. Albans, in the county of Franklin and State of Vermont, have invented certain new and useful Improvements in Bottles, of which the following is a specification.

This invention has for its object to provide a novel and improved closure for bottles designed to prevent fraudulent refilling thereof. A device is provided which, after the bottle is uncorked, prevents the same from being refilled without that fact being apparent. The bottle is closed by an ordinary cork or other stopper, which, when once displaced from its seat, is prevented from being replaced. Thus, a stopper cannot be applied to the bottle after the original stopper has been unseated, and a purchaser receiving a bottle having its stopper unseated, knows at once that the bottle has been emptied of its original contents and refilled.

The herein stated object is attained by means of a novel combination and arrangement of parts to be hereinafter described and claimed, reference being had to the accompanying drawing in which—

Figure 1 is a central vertical section of the bottle; Fig. 2 is a vertical section of the bottom portion of the bottle taken at a right angle to the plane of the section shown in Fig. 1, and Fig. 3 is a bottom plan view of the bottle.

Referring specifically to the drawing, 10 denotes the body of the bottle, the same having a neck at each end, the top neck being indicated at 11, and the bottom neck 40 at 12. The two necks are in alinement. The inner end of the neck 11 is tapered in order that an ordinary cork or other stopper 13 may be tightly wedged thereinto. An internal shoulder 14 at the junction of the neck 11 with the bottle body 10 prevents the stopper 13 from being pushed into the latter. The length of the neck 11 is such that there is sufficient room above the stopper 13 to accommodate a guard comprising a body 50 portion 15 having heads or enlargements 16 and 17, respectively, at its ends. In the neck 11, near the mouth thereof, is an annular shoulder 18 which is engageable by spring fingers or catches 19 carried by and 55 projecting outward and upward from the

guard body 15. When the guard is in position, the head 16 engages the top of the shoulder 18, and the fingers 19 the under side thereof, whereby the guard is prevented from being removed from the bottle neck, 60 and as it is located above the stopper 13, the latter can not be removed. The position of the shoulder 18 is such that the guard cannot be pushed into the neck a sufficient distance to reach the stopper. The diameter 65 of the head 17 is such that it may pass the shoulder 18.

The bottom neck 12 has a contracted inner end 20 forming a seat for a stopper 21, and the outer end of said neck is flared to provide a wide base 22 on which the bottle may be supported in upright position. In that portion of the neck 12, between the seat 20 and the base 22, is slidably mounted a stopper-displacer comprising a stem 23 having 70 heads or enlargements 24 and 25, respectively, at its ends. The diameter of the head 24 is such that it may enter the contracted neck portion in which the stopper 21 seats, and the head 25 fits snugly in the wide 75 portion of the neck. The neck 12, below the stopper seat 20, has two spaced annular shoulders 26 and 27, respectively, and the stem 23 carries spring fingers 28 similar to the fingers 19.

Inside the flared base 22 of the neck 12, on opposite sides of the mouth of the latter, are two transverse ribs 29 which extend convergingly to the edge thereof and serve 80 as pouring spouts.

The parts herein described are mounted in place as follows: The stopper-displacer 23 is inserted into the neck 12 from the bottom and pushed inward until the spring fingers 28 snap behind the first shoulder 26, whereby the displacer is locked against removal. The stopper 21 is now inserted through the neck 11 and seated, which can readily be done by using a small rod or stick having a sharp point to carry the stopper. The bottle 90 will now be filled, after which the stopper 13 is applied, and then the guard 15.

To pour out the contents of the bottle, the displacer 23 is pushed inward against the stopper 21 until the latter is unseated and 105 pushed into the bottle body 10, and the spring fingers snap behind the shoulder 27. The liquid can now be poured out of the bottle. The heads 24 and 25 have diametrically opposite longitudinal grooves 110

to permit the liquid to pass the same. The ribs 29 conduct the liquid to either side of the neck base 22 according to the direction in which the bottle is held tilted. In that 5 portion of the neck 12 between the shoulder 26 and the base 22 are diametrically opposite longitudinal ribs 31 to accommodate the grooves 30 of the head 25, the width of said grooves being such that the liquid can pass 10 therethrough.

Fig. 1 shows in dotted lines the position of the parts when the bottle is to be emptied of its contents. It will be noted that the 15 spring fingers 28 prevent the displacer 23 from being retracted, and as the stopper 13 is not accessible, in view of the guard 15, the bottle cannot be re-corked. Of course, there is nothing to prevent refilling of the bottle, but this fact will at once be apparent to the 20 purchaser by reason of the position of the stopper 21.

I claim:

1. A bottle having a neck, the outer end of which is flared to form a supporting base 25 for the bottle, said flared portion having internal transverse ribs on opposite sides of the mouth of the neck and extending to the edge of the base, and forming pouring 30 spouts, a stopper and a stopper-displacer in said neck, and means for locking the displacer against withdrawal from the neck.

2. A bottle having a neck at each end, stoppers seating in each neck, a guard for one of the stoppers to prevent unseating 35 thereof, a displacer for the other stopper mounted in the neck in which said stopper

seats, and means for locking the displacer against withdrawal from the neck.

3. A bottle having a neck at each end, one of said necks having an internal shoulder, a 40 stopper seating in each neck, a guard for the stopper which seats in the shouldered neck, said guard comprising a member having a head at its outer end seating on the corresponding side of the shoulder and having 45 catches engaging the other side of the shoulder, a displacer for the other stopper mounted in the neck in which said stopper seats, and means for locking the displacer against withdrawal from the neck. 50

4. A bottle having a neck provided with spaced internal annular shoulders and a seat for a stopper, and a stopper-displacer mounted in the neck and having catches successively engageable with the shoulders to prevent 55 its withdrawal from the neck, said shoulders being located different distances from the stopper seat.

5. A bottle having a neck provided with a contracted inner portion forming a stop- 60 per seat, a stopper-displacer mounted in the outer portion of the neck and having a head adapted to enter the stopper seat, said head having side grooves forming liquid passages, and means for preventing withdrawal of 65 the displacer from the neck.

In testimony whereof I affix my signature in presence of two witnesses.

MITCHEL E. DEVARNEY.
